UNITED STATES PATENT OFFICE

EDNA H. DICKSON, OF OAKLAND, CALIFORNIA

DESIGN FOR A BIRD-SERVICE UNIT

Application filed May 6, 1930. Serial No. 35,512. Term of patent 14 years.

To all whom it may concern:

Be it known that I, EDNA H. DICKSON, a citizen of the United States, and a resident of Oakland, in the county of Alameda and State of California, have invented a new, original, and ornamental Design for Bird-Service Units, of which the following is a specification, reference being had to the accompanying drawing, forming part thereof.

Figure 1 is an end perspective view of a bird service unit embodying my new design; and

Figure 2 is a side perspective view of the same.

I claim:

The ornamental design for a bird service unit, substantially as shown.

EDNA H. DICKSON.
